UNITED STATES PATENT OFFICE.

JOSEPH SOSS, OF BROOKLYN, NEW YORK.

TEE-FORMING DEVICE.

Application filed July 23, 1923. Serial No. 653,127.

To all whom it may concern:

Be it known that I, JOSEPH Soss, a citizen of the United States, and residing at Brooklyn, in the county of Kings and State of New York, have invented certain new and useful Improvements in Tee-Forming Devices, of which the following is a specification, such as will enable those skilled in the art to which it appertains to make and use the same.

This invention relates to devices for forming what are known as tees in teeing up a ball in the game of golf, and the object of the invention is to provide a device of this class which will facilitate the formation of and the placement of tees on a driving tee of a golf course without the hand of the player coming in contact with the sand, gravel or the like used for teeing purposes; a further object of the invention being to provide a device of the class and for the purpose specified which will facilitate the formation of a standard and uniform tee for a golf ball whereby at all times a golf-ball may be teed up to suit the player of the game; a still further object being to provide a device of the class referred to which will form a substantial body for teeing a golf ball and retaining the golf ball in predetermined position and against collapsing or movement especially when the ball is subjected to strong winds; and with these and other objects in view the invention consists in a device of the class and for the purpose specified which is simple in construction and operation and efficient in use, and which is constructed as hereinafter described and claimed.

The invention is fully disclosed in the following specification, of which the accompanying drawing forms a part, in which the separate parts of my improvement are designated by suitable reference characters in each of the views, and in which:—

Fig. 1 is a perspective view of one form of my improved tee forming device illustrating the method of its use;

Fig. 2 is a longitudinal partial sectional view through the device shown in Fig. 1 on an enlarged scale;

Fig. 3 is a plan view of the device shown in Figs. 1 and 2;

Fig. 4 is a sectional view through a tee formed by my improved device and showing a golf ball supported thereon;

Fig. 5 shows the tee illustrated in Fig. 4

in a depressed position with a golf ball mounted thereon; and,

Fig. 6 is a side view of a modified form of device which I employ.

In Figs. 1 to 3 inclusive, I have shown at 10 one form of my improved tee comprising a conical cup-shaped body 11 enclosed at its upper end as shown at 12 and provided with a radially extending handle member 13, and the cross head 12 is provided with an upwardly directed sleeve portion 14.

All of the above named parts are preferably formed integral and may be cast, forged or otherwise formed and, in practice, the cross head 12 is provided with an aperture 15 which opens into the sleeve portion 14 and mounted in the aperture 15 is a stem 16 of a plunger 17 which is tapered to fit in the tapered bore 18 of the cup-shaped body 11, and the stem 16 is provided at its outer end with an enlarged cylindrical head 19 against which a spiral spring 20, mounted within the sleeve 14, operates to normally hold the plunger 17 in a raised and seated position.

The lower face of the plunger 17 is preferably convex in form as shown at 21, and the periphery of the plunger is flared outwardly and downwardly as shown at 22 to form a sharp edge on said plunger to facilitate the cleaning out of the body of sand, gravel or the like 23 in the formation of a tee 24 as shown in Fig. 4 of the drawing.

In the use of my improved device the handle member 13 is grasped by the hand of the operator and the cup-shaped body 11 is passed into the sand in the usual sand boxes provided adjacent to the driving tees on a golf course, the lower face of the cup-shaped body is preferably pressed against one of the walls of the sand box or boxes to firmly compress a body of sand or similar material used in teeing up a ball in the cup-shaped body 11 as shown in Fig. 2 of the drawing, after which the thumb is placed upon the enlarged and protruding cylindrical portion 19 of the stem 16 of the plunger, and the lower face of the cup-shaped body 11 is placed slightly above the driving tee where it is desired to tee up the ball, at which time, the thumb of the hand is pressed downwardly to correspondingly move the plunger 17 which operation will release the body 23 of sand or similar material, and the same will drop upon and

rest on the driving tee in substantially the position shown in Fig. 4 of the drawing, and the convex face of the plunger forms a concave top 25 on the tee body 24, and this face forms a seat for the golf ball 26 shown in said figure.

From the foregoing it will be apparent that by providing a given chamber in the bottom face of the cup-shaped body 11 and below the lower face of the plunger 17, when in its seated position, a golf ball may be teed up a definite predetermined height at all times. If for any reason it should be desired to lower the teeing up of the ball this result may be accomplished by simply pressing downwardly on the ball 26 which will flatten out the tee body 24 substantially as shown at 27 in Fig. 5 of the drawing, but as the device may be made up in different sizes, each individual or player may have a device which will tee up a ball to suit his method of playing the game.

25 Aside from the fact that my improved device will facilitate the formation of a substantial and uniform tee at all times, I eliminate the inconvenience and objectionable feature of forming the tee by hand which is the common practice, which results in the soiling of the hands as well as the clothing or apparel of the player in endeavoring to free his or her hands of the sand or other material used for teeing purposes.

In Fig. 5 of the drawing I have shown a modification in which the cup-shaped body 11, sleeve portion 14, and plunger and the other parts mounted in connection therewith are exactly the same as that shown in Figs. 1 to 3 inclusive, and substituted for the handle member 13 are two oppositely disposed curved finger pieces 28 which extend from the top cross head portion 12 of the body 11, and I also employ two oppositely disposed feet members 29 which are curved downwardly and outwardly and extend from the lower portion of the body 11, and with this form of construction two of the fingers of a hand are placed beneath the finger members 28 and the thumb of the hand is placed upon the cylindrical portion 19 and in placing the body 23 upon a driving tee the device is first placed upon the tee, or with the foot members 29 resting thereon, after which the plunger is pressed downwardly by the thumb of the hand and the purpose of the foot members is to space the lower face of the cupshaped body 11 from the face of the driving tee in order that the teeing up body 24 may be dropped a short distance onto the driving tee and this construction will avoid the faulty manipulation of the device and, if desired, the foot members 29 may be used in connection with the device shown in Figs. 1 to 3 inclusive for the same purpose.

65 It will be understood that while I have

shown a specific form of construction for carrying my invention into effect, I am not necessarily limited thereto, as any suitable device in which a body of sand or similar material may be collected and discharged to form a teeing up body may be employed together with any suitable means for holding the device in the operation of placing the sand body therein and discharging the same therefrom, and various changes in and modifications of the construction herein shown and described may be made, within the scope of the appended claims, without departing from the spirit of my invention or sacrificing its advantages. 70 75 80

Having fully described my invention, what I claim as new and desire to secure by Letters Patent, is:—

1. A device of the class described comprising a cup-shaped member provided with a tapered bore, a plunger tapered to seat in said bore in a predetermined position, said plunger being provided with a part protruding through said member whereby the same may be actuated and the lower face of said plunger being convex in form, and the periphery of the lower edge of the plunger being flared outwardly and downwardly to form a sharp edge. 85 90

2. A device of the class described comprising a cup-shaped member provided with a tapered bore, a plunger tapered to seat in said bore in a predetermined position, said plunger being provided with a part protruding through said member whereby the same may be actuated, the lower face of said plunger being convex in form, the periphery of the lower edge of the plunger being flared outwardly and downwardly to form a sharp edge, and tensional means for holding the plunger normally seated in the bore of said member. 95 100 105

3. A device of the class described comprising a cup-shaped member provided with a tapered bore, a plunger tapered to seat in said bore in a predetermined position, said plunger being provided with a part protruding through said member whereby the same may be actuated, the lower face of said plunger being convex in form, the periphery of the lower edge of the plunger being flared outwardly and downwardly to form a sharp edge, tensional means for holding the plunger normally seated in the bore of said member, and said member being provided with a suitable handle portion. 110 115 120

4. A device of the class described comprising a cup-shaped member provided with a tapered bore, a plunger having a comparatively wide tapered face adapted to seat in said bore in a predetermined position, and the lower face of said plunger being convex in form and the periphery of the lower edge of said plunger being flared outwardly and downwardly to form a sharp edge. 130 125

5. A device of the class described comprising a cup-shaped member provided with a tapered bore, a plunger having a comparatively wide tapered face adapted to seat in 5 said bore in a predetermined position, the lower face of said plunger being convex in form and the periphery of the lower edge of said plunger being flared outwardly and downwardly to form a sharp edge, and members 10 projecting beyond the lower end of said cup member to provide means for spacing the discharge end of the bore a predetermined distance above a surface in the operation of the device.
15. 6. A device of the class described comprising a substantially cup-shaped member having a tapered bore which opens outwardly through one end of said member, said end of the member being provided with 20 parts projecting beyond the bore thereof and adapted to be placed on a predetermined surface to space the end of the bore a predetermined distance from said surface.
25. 7. A device of the class described comprising a substantially cup-shaped member having a tapered bore which opens outwardly through one end of said member, said end of the member being provided with independent parts projecting therefrom and 30 adapted to be placed on a predetermined surface to space the end of the bore a predetermined distance from said surface, and means seating in the bore of said cup-shaped member for discharging a body of predetermined material placed in said bore, therefrom.
35. 8. A device of the class described comprising a substantially cup-shaped member having a tapered bore which opens outwardly through one end of said member, said end of the member being provided with independent parts projecting therefrom and adapted to be placed on a predetermined surface to space the end of the bore a predetermined distance from said surface, 40 said end of the member being provided with independent parts projecting therefrom and adapted to be placed on a predetermined surface to space the end of the bore a predetermined distance from said surface, 45 means seating in the bore of said cup-shaped member for discharging a body of predetermined material placed in said bore, therefrom, said means involving a plunger, tensional means for normally holding said plunger in a seated position, and a suitable 50 hand piece for said cup-shaped member.
9. A device of the class described comprising a substantially cup-shaped member having a tapered bore which opens outwardly through one end of said member, said end of the member being provided with parts 55 projecting therefrom and adapted to be placed on a predetermined surface to space the end of the bore a predetermined distance from said surface, means seating in the bore of said cup-shaped member for discharging a body of predetermined material placed in said bore, therefrom, said means involving a plunger, tensional means 60 for normally holding said plunger in a seated position, a suitable end piece for said cup-shaped member, and the lower end of said plunger being convex in form and provided at the periphery with an outwardly 65 and downwardly flared sharp edge.

In testimony that I claim the foregoing as my invention I have signed my name this 20th day of July 1923.

JOSEPH SOSS.
